United States Patent Office.

GEORGE LITTLE, OF RUTHERFORD PARK, NEW JERSEY.

Letters Patent No. 96,330, dated November 2, 1869.

APPARATUS FOR PERFORATING PAPER FOR TELEGRAPHING.

The Schedule referred to in these Letters Patent and making part of the same.

To all whom it may concern:

Be it known that I GEORGE LITTLE, of Rutherford Park, in the county of Bergen, and State of New Jersey, have invented and made a new and useful Improvement in Perforating or Embossing Paper for Telegraphic Communications; and I do hereby declare the following to be a full, clear, and exact description of the said invention, reference being had to the annexed drawings, making part of this specification, wherein—

Figure 1 is a side elevation of the punching-apparatus, part of the frame being removed;

Figure 2 is a vertical section of the same, with the feed-magnet in elevation;

Figure 3 shows the reverse side of the relieving-magnets to that in fig. 1, representing the circuit-changer;

Figure 4 is a plan of the instrument below the line *xx*, fig. 1;

Figure 5 is a plan of a portion of the transmitting-tablet;

Figure 6 is an inverted plan of a portion of said tablet; and

Figure 7 is a vertical section of the same.

Similar marks of reference denote the same parts.

The object of this invention is to move the paper along by magnetism, independently of the perforation, which is also done by magnetism, so that the space between one perforation and the next is dependent upon one or more pulsations of electricity.

By this means the composing of a telegram for transmission can be accomplished by the working of two electric circuits by finger-keys, or otherwise, the one to perforate or emboss, the other to space.

It also enables me to employ a composing-tablet, formed with a series of conductors passing to the punching and feeding-magnets, in such alternations that the drawing of a stile or conductor over said composing-tablet, at the part allotted to the particular letter, will cause the respective magnets to be operative, in such a manner as to produce the proper perforated or embossed characters, with the requisite spaces for correctly designating the letter or character.

In the drawing, the frame *a* carries the feed-wheel *b*, that is made of iron or other material, with serrated edges or other surfaces, to feed the paper, and between these edges is a deep groove.

Below the feed-wheel is a standing column, *b'*, having a die, *c*, at its upper end.

c is the yielding presser and paper-guide, that keeps the strip of paper to the wheel *b*.

d *e* are guides on the edges of *c*, to keep the paper to its proper position.

The spring 2 keeps the presser up to its place, and the presser itself is on the boss or collar 3, so that it may yield and accommodate itself to the wheel *b* and paper.

Around the column *b'* is a sliding sleeve, *f*, with arms *f'*, that come upon each side of the paper, and connect with a cross-bar that is in the groove of the wheel *b*, and carries the punch *i*, to act with the die *c* in perforating or embossing the paper, the upward movement being limited by adjustable screws 5, shown by dotted line in fig. 1.

There is a small spring clearing-plate, 4, around the die, to press the paper off the die, as the latter rises.

Through a slot in the column *b'*, the lever *g* works freely, but is connected by a pin, 6, to the said sleeve *f*, and 7 is the fulcrum for said lever *g*, the same being upon one of the poles of the magnet *h*.

m is the armature of this magnet *h*, and *k k* are the armatures of the magnet *l*.

The magnet *l* acts to bring down the lever *g*, cylinder *f*, and punch *i*, and perforate the paper. The magnet *h* acts instantly to raise the parts to a normal position.

This last-named operation is performed by the circuit-changer *n*, that is formed by a lever acted upon by the lever *g*, so that when the magnet *l* is charged and draws down the armatures *k*, the lever *g* moves the circuit-changer *n* from the position shown in figs. 1 and 3, and so that the end rises into contact with the collar *s*, and this operation closes the circuit through the magnet *h*, as hereafter shown.

In order to move the feed-wheel *b*, I employ a magnet and swinging armature.

The poles *o*, of the magnet *o'*, stand on each side of the wheel *b*; and upon the axis *b'*, of the wheel *b*, a yoke, *p*, is fitted to swing, the same being drawn back from the magnet by the spring *q*, and arrested, at the proper point, by the adjusting-screw 10, that regulates the amount of the feed of the paper, each pulsation of electricity through the magnet *o*.

In the yoke *p* are the armature-clamps *r*, formed of iron or steel plates. They are shown as each hung on fulcrum-pins, *s*, (see fig. 2,) so that when the magnet *o* is charged, the clamps *r* are swung slightly on the pins *s*, and their edges grip the feed-wheel *b* and the yoke *p*, and that move together as the armature-clamps are drawn bodily toward the magnet *o*.

It will be seen, that when the wheel *b* is of iron, the armature is made of three parts, the feed-wheel *b* becoming a central portion to the armature *r*, one on each side, the parts becoming magnetized by induced magnetism, and the clamps *r* might slide edgewise to clamp the feed-wheel by magnetic induction, instead of swinging, if so desired.

Where the feed-wheel is not made of iron or steel, the armature-clamps only act to clamp and move the feed-wheel by friction that is increased by the induced electricity, which causes the armature-plates to press upon the sides of the feed-wheel.

The tablet which I employ for transmitting puls-

tions to the feeding and perforating-magnets consists of a tablet, *t*, of non-conducting material, with grooves or ranges of grooves.

I have shown two ranges and a portion of the table, and the respective grooves are allotted to letters or other characters, marked as seen in fig. 5.

Ranges of holes are bored along these grooves, or ranges of conductors introduced in the table. I have shown these conductors in the form of screws, *u u*, *v v*, but do not limit myself in this particular.

The conductors *u u* are connected with the binding-screw *w*, and the conductors *v v* are connected with the binding-screw *x*.

The mode of connection by the ranges of wires will be apparent by inspection of fig. 6, the wires being intertwined under the heads of the screws to which they connect, and kept entirely clear of those with which the other wires connect.

When the current is closed through a screw, *u*, a pulsation goes to the magnet *l*, to perforate the paper, and, when through *x*, the pulsation goes through *o* to feed the paper, and these conductors *u* and *v* are so disposed that the proper perforations and spaces are produced to denote the given character or letter. Thus a perforation and then two pulsations of the feed make two separate perforations; the alternate pulsations make a dash; and more than two pulsations through *o* make spaces of length proportioned to the number of pulsations.

In order to close the circuit to the conductors *u v*, I make use of a conductor or metal stylus, with a flexible conductor *v'*. The lower part of this stylus is shown in fig. 7, at *w'*.

One battery-wire and conductor *v'* go to the binding-screw 20; the other battery-wire connects with the metal frame *a*, at 21.

The binder *x* connects with 22, and the binder *w* with 23.

The electricity goes from 20, through *v'* and *w'*, to the conductors *u* or *v*, as the stylus is drawn over them.

When the current passes through a conductor, *u*, it goes by *w* to 23, which is insulated, through magnet *l*, to the frame *a*, thence, by 21, to the battery.

The magnet *l* draws down *g*, punching the paper, lifting the circuit-changer *n*, causing a current to pass from frame *a*, through *g* and *n*, insulated collar 8, conductor 24, also insulated, through the magnet *h*, and thence to the insulated binder 20, thus drawing down the armature *m*, lifting the punch, and restoring the parts to their normal condition, also breaking the circuit by moving the changer *n*.

When the stylus *w'* is in contact with a conductor, *v*, the pulsation goes, through *v' w' v x*, to the insulated binding-screw 22, thence through the wire to the magnet *o'*, moving the paper by the armature-clamp and feed-wheel; thence the electricity passes to the frame *a*, binder 21, to the battery, without affecting the magnets *h* or *l*.

By this means the feed is effected by one magnet, the punching by another, and the relieving of the punch by a third and self-acting magnet; and I remark that

the tablet is preferred for sending the pulsations of electricity, but a double-acting finger-key or two finger-keys, such as shown in Figure 8, might be worked by an experienced operator, or two binding-screws, as in Figure 9, might be used, to be touched by the stylus *w'*, alternately, or the tablet might be employed with some other arrangement of mechanism for perforating the paper by the action of magnetism.

This tablet can stand on a person's desk, and the composing-machine be in any desired distant place, thus giving great convenience in composing telegrams.

The armature-wheel *b*, that moves the paper along by the direct action of the magnetism, might have ratchet-teeth at its side, acted upon by pawls on the swinging armature *p*, or the plate *r* may be loose, to slide in grooves and attach themselves to the wheel *b*, by induced magnetism, simultaneously with the movement of the armature, as it swings on the same axis as the wheel *b*.

The axis of the swinging armature and clips may be located on the line of the axis of the wheel *b*, but separate from the same.

What I claim, and desire to secure by Letters Patent, is—

1. A wheel for feeding along a strip of paper to be perforated, in combination with an armature swinging on the same axis as the feed-wheel, and an electro-magnet, substantially as set forth.

2. The punch *i* and presser-plate *e*, in combination with the feed-wheel *b*, die *c*, and sleeve *f*, substantially as and for the purposes set forth.

3. The magnets *h* and *l*, arranged as specified, in combination with the lever *g*, on the fulcrum 7, that is one pole of the magnet *h*, and with the circuit-changer *n*, substantially as and for the purposes set forth.

4. An apparatus for composing telegraphic communications, consisting of a magnet, lever, punch, and die, to perforate or emboss the paper, in combination with a feed-wheel and an electro-magnet, to move said feed-wheel progressively, substantially as set forth.

5. Mechanism for feeding the paper by magnetism, and mechanism actuated by an electro-magnet, for perforating the paper, in combination with mechanism, for closing the circuits to the respective magnets in, such an alternate manner as to compose a telegraphic communication on a strip of paper, substantially as set forth.

6. The tablet *t*, formed of conductors, arranged substantially as set forth, in combination with a movable stylus or circuit-closer that is to be moved, in contact with the conductors of the tablet, to produce alternate pulsations of electricity for feeding the paper and punching the same by magnetism.

In witness whereof, I have hereunto set my signature, this 7th day of April, 1869.

GEORGE LITTLE.
